UNITED STATES PATENT OFFICE.

CHARLES HOWARD FUNKEY, OF RAMSAY, MICHIGAN.

MINE-CAR-LOADING SHOVEL.

1,390,695.

Specification of Letters Patent. Patented Sept. 13, 1921.

Application filed February 18, 1920. Serial No. 359,744.

To all whom it may concern:

Be it known that I, CHARLES HOWARD FUNKEY, a citizen of the United States, residing at Ramsay, in the county of Gogebic, 5 State of Michigan, have invented a new and useful Mine-Car-Loading Shovel; and I do hereby declare the following to be a full, clear, and exact description of the invention, such as will enable others skilled in the art 10 to which it appertains to make and use the same.

The invention relates to loading shovels for mine cars and has for its object to provide a shovel of this character which will be 15 compact in form and of such a size that the same may be used in tunnels or drift headings of mines whereby the broken materials may be shoveled rearwardly into the mine car. It being the present practice to shovel 20 the broken material into the cars manually which requires considerable time and several men.

A further object is to provide a mine car having a longitudinal slidable cross head 25 slidable on cross head guides carried on top of the cars, said cross head having pivotally mounted therein a transversely slidable yoke, which yoke carries an air cylinder having a shovel carrying piston mounted 30 therein, and to provide means whereby the cross head and shovel may be simultaneously moved toward the front of the car during a shoveling operation. Also to provide means whereby the transversely slidable 35 yoke may be moved transversely and the cylinder carrying the shovel piston tilted upwardly or downwardly at its forward end so that said shovel may be placed in engagement with the broken material on the mine 40 floor and dragged rearwardly into the car.

A further object is to provide a tiltable hopper at the forward end of the car, up the inclined bottom of which the material will be dragged during a shoveling and loading 45 operation, said hopper being controlled by a lever whereby it may be tilted upwardly or downwardly as desired. A further object is to provide a pivoted door at the rear end of the car through which the material may be 50 moved from the car, after said car has been moved to any position desired.

A further object is to provide means whereby the cross head and shovel piston may be simultaneously operated from a 55 single source of power, and means whereby said power may be controlled.

A further object is to so position the cylinder on the cross head and the cylinders carried by the sides of the car which move said cross head so that when pressure is admitted to said cylinders simultaneously, the speed of forward movement of the shovel will be greater than if only the shovel piston or the cross head controlling piston were singly operated.

With the above and other objects in view the invention resides in the combination and arrangement of parts as hereinafter set forth, shown in the drawings, described and claimed, it being understood that changes in 70 the precise embodiment of the invention may be made within the scope of what is claimed without departing from the spirit of the invention.

In the drawings:—

Fig. 1 is a side elevation of the car and shovel carried thereby.

Fig. 2 is a top plan view of the car.

Fig. 3 is a front elevation of the car.

Fig. 4 is a perspective view of the air 80 pipes leading from the control valve to the air cylinders.

Fig. 5 is a detail perspective view of the door hook.

Fig. 6 is a perspective view of the tiltable 85 scoop.

Fig. 7 is a horizontal sectional view through a conventional form of four-way valve for controlling the movement of the shovel piston and the cross head pistons.

Referring to the drawings, the numeral 1 designates the body of the mine car and 2 a wheeled truck to which the body 1 is pivoted as at 3, so that the body of the car may be pivoted around in a horizontal plane 95 when desired. The forward end of body 1 is open as shown at 4 and the bottom of the body is provided with a downwardly and forwardly extending inclined portion 5^a. Pivoted as at 6 to the inclined portion 7 is 100 a hopper 8, said hopper having upwardly extending sides 9, which prevent the material as it is dragged into the car body during a shoveling operation from being forced transversely and out of registration with the front of the car body. The hopper 8 has pivoted to one of its sides 9 as at 10 a link 11, which link has its other end pivotally connected as at 12 to the arm 13 of an operating lever 14, preferably a foot actuated 110 lever. Lever 14 has sufficient flexibility so that the lug 15 may slide over teeth 16 of a

rack 17 secured to the side of the body of the car so that the hopper 8 may be maintained in any position to which it may have been moved. The normal function of the hopper 8 is to provide an extension to the inclined bottom 5 of the body so that the material may be dragged up the inclines of both the body and the hopper into the main car body. An additional function of the 10 hopper 8 is after the mine car has been filled the hopper 8 when moved upwardly forms a closure for the front opening 4 of the body.

Pivoted as at 18 to the rear ends of the sides 19 of the body 1 of the car is a closure 20, which closure is adapted to be swung open as shown in dotted lines in Fig. 1 when it is desired to shovel or remove the mined material from the car after the same has been transported from the mine. Pivoted to 15 the under face of the car body as at 21 between ears 22 is a weighted hook 23, the weighted end 24 of which normally holds the hooked end 24^a upwardly and in engagement with a lower marginal edge of the pivoted closure 21. Hook 23 normally holds the closure 20 closed. However, when it is desired to open the closure it will only be necessary to place a foot on the hooked end 24^a and force the same downwardly, which will 20 release the closure 20.

Secured to the upper ends of the sides 19 and held spaced therefrom by means of lugs 25 are cross head guides 26 which guides extend longitudinally of the car and have longitudinally slidable thereon a cross head 27, which cross head is provided with L-shaped ends 29 which overlie the outer faces of the guides 26, thereby preventing displacement of the cross head as the same is reciprocated 30 on the guides 26. Secured to the lower ends of the L-shaped members 29 of the cross head by means of bolts 30 are guide bars 31 which bars engage the under edges of the guides 26. Guide bar 31 extending forwardly substantially to the center of the body 1 and is provided with L-shaped members 32 which overlie the upper edges of the cross head guide 26 thereby additionally bracing the guide bars 31 as the same are 35 reciprocated. Pivotedly secured to the forward ends of the guide bars 31 as at 33 are rearwardly extending piston rods 34. Piston rods 34 are disposed in air cylinders 35 and are provided with pistons 36 which are adapted to be reciprocated so that the cross head 27 may be moved forwardly and rearwardly during a shoveling operation. Cylinders 35 are secured to the sides 19 of the body of the car by means of brackets 37. 40 However, the cylinders 35 are of conventional form and although the same are described as air cylinders, it is to be understood that steam or fluid may be utilized for driving the pistons 36.

65 Rising upwardly from the cross head 27

are spaced brackets 38 in bearings 39 of which the pintles 40 of the shovel cylinder 41 are pivotally mounted and also transversely slidable. By pivotally and slidably mounting the pintles 40, it will be seen that 70 the shovel cylinder may be tilted vertically during a shoveling operation and also moved transversely so that shoveling of the material from the ground may be accomplished for the full width of the mine car. Shovel 75 cylinder 41 has slidably mounted in a bearing 42 thereof a piston rod 43, which piston rod is provided with a conventional form of piston 44 adapted to be reciprocated within the shovel cylinder 41 so that said piston 80 rod 43 may be moved forwardly and rearwardly during a shoveling operation. Secured to the forward end of the piston rod 43 as at 45 is a transverse portion 46 of a U-shaped member 47, the arms 48 of said 85 U-shaped member being slidably mounted in guides 49 carried by the shovel cylinder 41. Arms 48 as the shovel 50 is forced downwardly into the broken material, located forwardly of the car and is then dragged rearwardly so as to drag the material into the car, form means for bracing the shovel during these operations. The U-shaped member 37 is provided with brace members 51 for bracing its corners. Shovel 50 is bolted as 90 at 52 to the portion 46 of the U-shaped member 47 so that said shovel may be easily removed and replaced with another shovel when the same becomes worn or broken. Secured to the outer end of one of the pintles 100 40 is an operating lever 53, which lever is adapted to be grasped by the operator when it is desired to move the shovel cylinder 41 transversely and also adapted to be used by the operator for tilting the cylinder 41 in 105 a vertical plane during a shoveling operation. It is contemplated to manually control the shovel during a shoveling operation, and the parts so balanced and made of such a size so that this will be possible. As the 110 car is adapted to be used in drift headings and the like of mines, it will be seen that the same will not be extremely large.

Air for operating the pistons 36 and 44 is obtained from any suitable source through 115 a flexible hose which may be connected at 54 to the pipe 55, which pipe leads to the intake opening 56 of a four-way valve 57. The air passes upwardly through the intake opening 56 and through the port 58 so that 120 the air will pass into the pipe 59 from which pipe 59 it will pass to the forward end of the cylinders 35 and 44 through the pipes 60 and 61. Air being admitted to the forward ends of the cylinders 35 and 44 it will be seen that 125 the pistons 36 and 44 will be forced rearwardly, thereby moving the shovel 50 rearwardly. However, when the port 58 is placed in registration with a pipe 59, an exhaust port 62 is placed in registration with the pipe 63, 130

which pipe 63 is connected with the rear end of the cylinders 35 and 44 by means of pipes 64 and 65, therefore as the pistons 36 and 44 are moved simultaneously rearwardly, the 5 air from the rear end of the cylinders will be exhausted through the pipe 63, exhaust port 62 and outlet port 66 to the atmosphere. When the air port 67 is placed into registration with the pipe 63 the action is reverse 10 and the pistons 36 and 44 forced forwardly, the air from the other ends of the cylinders exhausting through the pipe 59, exhaust portion 62 and exhaust outlet 66. When the 15 valve-control lever 68 is in the position of the dotted line *a* as shown in Fig. 7, the pistons 36 and 44 will be simultaneously moved rearwardly, however, when the lever 68 is in the position of the dotted line *b* in Fig. 7 the action will be reversed, therefore it will be 20 seen that the shovel and cross head may be simultaneously moved forwardly and rearwardly as desired so that the same will be under complete control of the operator. When it is desired to stop the shovel and 25 cross head in any position all that is necessary is for the operating lever to be placed in the position as shown in Fig. 4, at which time, both ports 58 and 67 will be out of registration with the pipes 59 and 60, which 30 pipes will be closed at their ends by the rotatable valve. Lever 68 is controlled by means of a connecting rod 69, one end of which is pivoted to the lever 68 as at 70 while the other end is pivoted as at 71 to a 35 hand lever 72, which lever in turn is pivoted as at 73 to the side 19 of the body 1. It will be seen that the four-way valve 57 will at all times be completely under the control of the operator through the medium of the lever 72.

40 It will be seen that as the cylinder 41 is carried by the cross head 27, which cross head is moved forwardly simultaneously with the outward movement of the piston rod 43, that the shovel will be rapidly advanced and moved rearwardly during a shoveling operation, thereby getting the maximum of reach and at the same time insuring the rapidity of action. During the 45 operation of the device the shovel cylinder 41 is moved forwardly to the dotted line position and pivoted upwardly at its forward end as shown by the dotted line *C*, as shown in Fig. 1, however, the upward pivoting of the outer end is not absolutely essential.

50 Then the forward end of the shovel cylinder 41 is tilted downwardly as shown in dotted lines in Fig. 1 until the shovel 50 is embedded in the material located forwardly of the hopper 8. The shovel being embedded 55 in the material the four-way valve is then moved so that the cross head 27 will again be moved rearwardly and also the piston rod 43, so that the material behind the shovel 60 will be dragged into the body 1 of the mine car. During this backward dragging of the 65

material the shovel cylinder 41 and shovel are controlled by the operator through the medium of the lever 53.

From the above it will be seen that a mine car is provided with a loading mechanism, 70 which loading mechanism is extremely simple in construction and may be easily controlled by one man. By providing such a car it will be possible to rapidly load the cars and eliminate the present practice of manually shoveling the material into the cars. By so positioning the shovel and operating the same, it will be seen that the car may be worked in drift headings and tunnels.

The invention having been set forth what 80 is claimed as new and useful is:—

1. The combination with a mine car, of longitudinal disposed guides carried by said car, a longitudinally movable cross head mounted on said guides, a cylinder transversely pivoted in said cross head, said cylinder being transversely movable in parallel relation to the cross head and provided with a reciprocating piston having a piston rod connected thereto, the forward end of said piston rod being provided with a shovel, air cylinders carried by the car, a piston and piston rod disposed in said air cylinders, said piston rod being connected to a cross head, means whereby pressure may be applied to said cylinders for simultaneously moving the cross head and the shovel and means whereby the transversely pivoted cylinder may be controlled in a tilting action during a shoveling operation. 95

2. The combination with a mine car, of a longitudinally movable cross head mounted on guides of said car, a transversely pivoted air cylinder pivoted in bearings of the cross head, said cylinder being transversely movable in parallel relation to the cross head, a reciprocating piston rod in said cylinder, said piston rod being provided with a downwardly extending shovel, air cylinders carried by the car and provided with reciprocating piston rods, said piston rods being connected to the cross head, means whereby the piston rods of all the cylinders will be simultaneously reciprocated and means whereby the shovel cylinder may be tilted 105 and controlled during a shoveling operation. 110

3. The combination with a mine car, of a longitudinally movable cross head mounted on guides of said car, a transversely pivoted air cylinder pivoted in bearings of the cross head, said cylinder being carried by pintles which are transversely slidably in the bearings of the cross head, a reciprocating piston in said cylinder, and carried by a piston rod, a shovel at the end of the piston rod and extending downwardly, air cylinders carried by the car and provided with reciprocating piston rods, said piston rods being connected to the cross head, 120 125 130

means whereby the piston rods of all of the cylinders may be simultaneously reciprocated for extending the shovel forwardly and moving the cross head forwardly on its guides, and means whereby the shovel carrying cylinder may be tilted and controlled during a shovel operating and also moved transversely in its bearings.

4. The combination with a mine car, of a longitudinally movable cross head mounted on guides of the car, said guides being disposed above the car body, a transversely pivoted air cylinder pivoted in bearings of the cross head, said cylinder being transversely movable in parallel relation to the cross head, a reciprocating piston rod in said cylinder, said piston rod being provided with a downwardly extending shovel, air cylinders carried by the car and provided 10 with reciprocating piston rods, said piston rods being connected to the cross head, means whereby the piston rods of all of the cylinders may be simultaneously reciprocated and means whereby the shovel cylinder 15 may be tilted and controlled so that material located in front of the car may be dragged into said car.

5. The combination with a mine car, of a cross head mounted on said car, an extensible shovel transversely pivoted and transversely movable in parallel relation to the cross head and in said cross head, and means for simultaneously extending the shovel and moving the cross head.

35 6. The combination with a mine car, of a cross head mounted on said car, an extensible shovel transversely pivoted in the cross head, said shovel being transversely movable in parallel relation to the cross head, means 40 for simultaneously extending the shovel and moving the cross head in the same direction, and means whereby the extensible shovel may be controlled during a forward and rearward movement of said shovel and cross head.

45 7. The combination with a mine car, of a

cross head mounted on said car, an extensible shovel transversely pivoted in the cross head, means whereby the extensible shovel may be moved transversely in parallel relation to the cross head, and vertically, means carried by the car and connected to the cross head for moving said cross head, and means whereby the cross head and the extensible shovel may be simultaneously operated.

8. The combination with a mine car pivoted on a truck, of a cross head mounted on said car, an extensible shovel transversely pivoted and transversely slidale in the cross head, means for moving the extensible shovel transversely and pivoting the same vertically, means carried by the car and connected to the cross head for moving said cross head and means whereby said cross head and extensible shovel may be simultaneously moved forwardly and rearwardly during a shoveling operation.

9. A mine car comprising a body, said body being pivotally mounted on a wheeled truck, the forward end of said car being open, the rear end of said car being provided with a pivoted closure, a scoop pivoted to the forward end of the car, means for lowering and raising said scoop, detent means for holding the closure at the rear end of the car normally closed during a loading operation, a piston carried shovel longitudinally movable on guides carried by the upper ends of the sides of the car, and means whereby said piston carried shovel may be moved forwardly, downwardly and rearwardly so that broken material may be dragged up the pivoted scoop into the mine car body.

In testimony whereof I have signed my name to this specification in the presence of two subscribing witnesses.
